PROCESS FOR TREATING HYDROCARBONS

Walter A. Schulze and Lloyd C. Morris, Bartlesville, Okla., assignors to Phillips Petroleum Company, a corporation of Delaware

Application October 28, 1941, Serial No. 416,882

19 Claims. (Cl. 196—24)

This invention relates to the desulfurization of hydrocarbon liquids of the nature of gasoline. More specifically it relates to the production of hydrocarbon stocks of lowered sulfur content and improved response to anti-detonants by a novel arrangement and revision of manufacturing operations which produce said stocks from crude petroleum oils, natural gas or hydrocarbons from any source. The invention has particular application to the segregation of blending components for the manufacture of motor fuels of very high anti-knock qualities wherein the maximum benefits of desulfurization are realized.

The importance of sulfur removal from gasoline and special motor fuels of all types has been emphasized by the increasingly higher anti-knock specifications and the practically universal use of anti-detonant additives such as tetraethyl lead. It has been established that the octane number improvement obtained by addition of lead alkyl anti-detonants to motor fuels is dependent on the total amount and kind of sulfur compounds in said fuels, and that tremendous savings result from the reduction of the sulfur content of hydrocarbon oils used in the production of said fuels.

The benefits derived from desulfurization may be measured in terms of decreased amounts of tetraethyl lead required to produce a given octane rating. In other applications, the benefits may be measured in increased volumes of fuels produced according to specifications limiting the concentration of anti-detonant compound. In either instance, the manufacture and/or segregation of hydrocarbon oils of low sulfur content and high octane rating have become related problems to the refiner.

The trend toward higher octane ratings and the manufacture of special fuels have led to processes involving synthesis of certain hydrocarbons such as iso-octane and the like, and to rather elaborate procedures for the segregation of the more desirable hydrocarbons occurring in complex mixtures such as crude oil and natural gasoline. For example, in the manufacture of 100 octane fuels containing a maximum of 3 ml. per gallon of tetraethyl lead fluid, commercial iso-octane is ordinarily one component. Other hydrocarbons, such as isopentane, are blended with the iso-octane to furnish the desired volatility, and special naphtha fractions are generally added to increase the volume of the blend to the limit conforming to the specifications on octane number and tetraethyl lead concentration. In such operations, the total volume of fuel which can be prepared from a unit volume of iso-octane will depend upon the

octane number and the sulfur content of the other components. Thus the sulfur content of the blending stocks is of major importance, and justifies the use of extensive desulfurization treatment.

Various chemical treating processes have been proposed for reducing the sulfur content of hydrocarbon oils and some of these have specific application to certain refining operations for ordinary motor fuels. Also catalytic processes have been proposed which accomplish desulfurization by more or less severe treatment of hydrocarbon oils at elevated temperatures. These prior processes often are justified in that the savings obtained are greater than the cost of equipment, product losses, and operation. However, in many cases a more efficient and inexpensive method of desulfurization is desirable.

We have now discovered a process whereby the desulfurization of hydrocarbon oils valuable as high octane number blending stocks can be caused to coincide with the operations which produce and/or segregate said stock from complex hydrocarbon mixtures. By our method of operation, the major part of the desulfurization occurs in the particular mode of separation of high octane stocks from low octane stocks so that said high octane stocks may not require further desulfurization treatment. However, our process provides for additional sulfur reduction if it is desirable. Our invention is to a large extent based on a novel interpretation of the boiling point, volatility and partial pressure relationships exhibited by the sulfur compounds in hydrocarbon mixtures and extends conventional treating and fractionation methods to accomplish desulfurization.

The principal object of the present invention is to provide an improved process of preparing an isopentane blending stock. Another object is to provide an improved process of freeing isopentane from sulfur at the same time as or in conjunction with its preparation. Another object is to provide a process for simultaneously preparing low sulfur-content isopentane blending stock and low sulfur-content pentane-free gasoline. Still another object is to provide an improved process of desulfurization. Another object is to provide an improved process of preparing blending stocks high in iso-paraffins above C₅ and simultaneously a blending stock high in isopentane and obtaining as a by-product a blending stock high in n-pentane. Numerous other objects will more fully hereinafter appear.

This invention may be understood from the following description taken in conjunction with

the accompanying drawing which portrays diagrammatically one form of equipment which has been found suitable for carrying out the process of the invention.

In one aspect, the present invention involves fractionating an unsweetened butane-free and hydrogen-sulfide free gasoline stock containing mercaptans and alkyl sulfides including methyl sulfide, to recover as the overhead product a pentane fraction in which the low-boiling sulfur compounds appear and a bottom product of hexanes and heavier containing the high-boiling sulfur compounds. The pentane fraction so formed is then sweetened to convert the mercaptans therein to high-boiling disulfides, and the sweetened pentanes are then fractionated to form an overhead product consisting essentially of isopentane in which unexpectedly the methyl sulfide appears (in view of its boiling point this compound would not be expected to appear in the isopentane but to remain in the bottom product) and a bottom product comprising n-pentane and the high boiling disulfides. The isopentane fraction thus obtained may then be dehydrated and subjected to the action of anhydrous cupric chloride to remove the methyl sulfide therefrom and give a blending stock consisting essentially of isopentane and generally containing less than 0.0001% of sulfur. The isopentane fraction prior to treatment for removal of methyl sulfide usually contains less than 0.01% of sulfur and for many purposes this low sulfur content, which is mainly attributable to the presence of methyl sulfide, is not objectionable in which case the step of removal of the methyl sulfide may be dispensed with.

The bottom product of hexanes and higher from the original fractionation of the sour gasoline is subjected to a sweetening treatment to convert the mercaptans to disulfides, and the sweetened product is subjected to fractionation to form one or more fractions comprising hydrocarbons of C₆ to C₈ including iso-hexanes and iso-heptanes, for example either a single fraction of pentane-free gasoline or a plurality of fractions comprising an iso-hexane fraction and an iso-heptane fraction, and perhaps even an iso-octane fraction. This fraction or fractions comprising one or more iso-paraffins may be treated as before for removal of alkyl sulfides, if desirable. The bottom product from this fractionation may comprise the n-hexane, n-heptane and heavier hydrocarbons and the very high boiling sulfur compounds particularly the disulfides formed in the sweetening step.

My process takes advantage of the discovery that the distribution of the mercaptans in the first fractionation departs from the expected one and involves the appearance of a larger-than-expected percentage of the mercaptans in the light overhead pentane fraction and of a smaller-than-expected percentage in the heavy bottom. In addition, the separation of hydrocarbons at a given boiling point involves simultaneous separation of mercaptans at a materially higher boiling point. Thus sulfur compounds boiling materially above 97° F. (the boiling point of n-pentane), even as high as 155° F., come over with the pentanes.

This departure from expected behavior in the separation of the pentane fraction is taken advantage of, in accordance with my invention, by subjecting the pentanes to a sweetening step to convert the mercaptans therein to disulfides thereby producing such a great difference in boil-

ing point between the disulfides formed and the isopentane that fractionation of the sweetened pentanes effects production of isopentane free from disulfides. However the methyl sulfide unexpectedly appears largely in the isopentane fraction so produced and, if excessive in amount, is preferably removed by treatment of the anhydrous isopentane with anhydrous cupric chloride.

The unexpected distribution of the mercaptans and other sulfur compounds, referred to above, results in a lower concentration and a higher average boiling point of mercaptans in particular, in the bottom product from the first fractionation. Upon sweetening this bottom product such relatively high boiling mercaptans as are present are converted to disulfides of very high boiling point. Upon fractionation of this sweetened bottom product these very high-boiling sulfur compounds are very readily separated from the gasoline and appear in the heavy bottoms. Also, in view of the low concentration of these disulfides in the sweetened bottoms, their distribution in accordance with known distribution laws causes them to be absent from the light overhead gasoline product in detectable amounts. However the higher-boiling alkyl sulfides may go overhead and appear in the pentane-free lighter fraction or fractions in objectionable amounts, although usually the amount of alkyl sulfides in the overhead product to 10% bottoms will be less than 0.015%. Treatment of this overhead product with anhydrous cupric chloride reduces the sulfur content to not over 0.010%. Whether the overhead product is recovered as such or in the form of individual fractions of isohexanes, iso-heptanes and n-hexane, or of the isoheptanes and isoheptanes in admixture with the n-hexane recovered separately, it is preferred that such isoparaffinic stocks have a sulfur content of less than 0.010%. As brought out below, if the components are separately recovered and then blended, a lower sulfur content is possible than where they are recovered together.

As stated previously, special high octane fuels are often prepared by blending synthetic iso-octane with other stocks chosen for high octane number and proper boiling range and often segregated in relatively pure form. Our invention will be described in terms of such an operation, although the basic principles are of wide scope and general application. For our process, any low-boiling liquid hydrocarbon mixture preferably in the gasoline range, such as straight run, natural, polymer, or vapor recovery gasoline, may be the starting material. However, we ordinarily prefer a natural or straight run gasoline containing maximum amounts of isoparaffins and minimum amounts of olefins and cyclic hydrocarbons which complicate the desired separations.

A hydrocarbon mixture of the described nature is the gasoline separated by conventional methods from natural gas and termed natural gasoline. For our purposes, the natural gasoline should be substantially free of butane and lower boiling hydrocarbons and have a boiling range of from about 70° to about 300° F. Often the retention of slight amounts of absorption oil will raise the end point of such gasoline to higher values. Those familiar with the industry will recognize this gasoline as so-called 12 pound (Reid vapor pressure) or "butane-free natural." Such gasoline is a common source of pentanes, pentane-free gasoline and of oil-free pentane-free gasoline.

This mixture may comprise varying amounts of some or all of the following hydrocarbons listed below with their approximate boiling points and octane numbers.

Hydrocarbon	Boiling point °F. @760 mm.	A. S. T. M. octane number
Isopentane	82	90
n-Pentane	97	61
Isohexanes	120 to 150	73 to 96
n-Hexane	155	25
Isoheptanes	175 to 200	82 to 100
n-Heptane	210	0
Octanes and nonanes	211 to 300 and higher.	

The higher boiling hydrocarbons of 8 or more carbon atoms are not ordinarily considered for careful segregation of a single component because of the increasing complexity of the mixture and the higher boiling points, although in some cases it may be desirable to extend the process of separation to include isoparaffins of high octane number in this or higher boiling ranges. It will be seen from the above table that the least desirable components of the mixture from the standpoint of octane number are the normal paraffins. Thus, isopentane is the most desirable component to furnish high octane number and volatility in a blend, while normal pentane is less desirable. Similarly the iso-hexanes and isoheptanes are particularly desirable for the special naphtha blending stocks, and n-heptane is the least desirable constituent. In view of these considerations, a preferred procedure is to segregate the isopentane and the fractions comprising iso-hexanes and isoheptanes up to some predetermined maximum boiling point. The n-pentane, n-hexane, n-heptane and the high-boiling ends of the gasoline, which are thus excluded, may then be further processed or used for other purposes wherein the low-octane number or unsatisfactory boiling range are not undesirable.

The same natural gasoline described above would ordinarily be free of hydrogen sulfide following removal of butane, the hydrogen sulfide being removed prior to, at the same time as, or after the butane. Some methyl mercaptan would also be removed in the butane separation. The remaining sulfur compounds would include the following:

Sulfur compound	Boiling point °F. (760 mm.)
Methyl mercaptan	43.2
Ethyl mercaptan	98
Methyl sulfide	100
i-Propyl mercaptan	139
t-Butyl mercaptan	153
n-Propyl mercaptan	154.4
Isobutyl mercaptan	190
Ethyl sulfide	198
n-Butyl mercaptan	208

When the sour stock is sweetened by conventional sweetening procedures the lower-boiling mercaptans are converted to the corresponding disulfides having the following boiling points:

Compound	Boiling point °F. (760 mm.)
Dimethyl disulfide	244
Diethyl disulfide	307
Di-isopropyl disulfide	347

Thus, higher-boiling mercaptans are converted to disulfides having still higher boiling points beyond the designated boiling range of the gasoline and hence concentratable in the highest boiling fraction.

5 In accordance with our invention the sour hydrocarbon mixture is fractionated prior to sweetening in an operation which produces an overhead fraction consisting of C₅ hydrocarbons and a bottoms fraction comprising substantially pentane-free material. A sharp separation is essential to remove substantially all of the n-pentane from the bottoms fraction.

10 In this fractionation of the sour gasoline, methyl and ethyl mercaptans are substantially removed from the hexanes and heavier fraction and taken overhead with the mixed pentanes, whereas if the butane-free gasoline is sweetened prior to the de-pentanizing step, the dimethyl and diethyl disulfides formed remain to a large extent in the hexane and heptane fractions. Thus, by the mode of operation described herein, methyl and ethyl mercaptans are treated in a manner that makes possible their removal from the high octane iso-paraffin stocks.

15 Following the fractionation, the C₅ hydrocarbon fraction is sweetened by a conventional method to convert the mercaptans to the corresponding disulfides. The pentane fraction is then 20 fractionated in equipment which provides excellent separation between the isopentane which is taken overhead and the n-pentane which is the kettle product. The isopentane is ordinarily above 80 per cent pure, and over 95 per cent 25 purity is obtainable if desired. The n-pentane which contains the major portion of the sulfur compounds distributed in the C₅ fraction by the initial fractionation, may be employed for blending with lower octane fuels. It will usually be 30 desirable to fractionate the n-pentane in order to obtain as the overhead product n-pentane essentially free from sulfur and as the bottom product containing the relatively high-boiling sulfur compounds.

35 40 45 The valuable isopentane concentrate following the described operation ordinarily has a low sulfur content, containing substantially only methyl sulfide. This impurity may then be removed by means of anhydrous cupric halide reagents as described in our copending application, Serial Number 318,648, of which this application is a continuation-in-part, and isopentane substantially sulfur free is thereby produced. The method of that application comprises contacting the sweetened hydrocarbon oil in substantially anhydrous form with a reagent comprising substantially anhydrous cupric chloride to remove the alkyl sulfides from the sweetened oil.

50 55 60 65 The substantially pentane-free mixture from the original fractionation is then sweetened in a separate unit and the sweetened mixture is fractionated to remove heavy ends and/or to segregate the high-octane iso-paraffins. The extent and the sequence of the fractionation operations may vary with the volume and quality of the special naphtha cuts desired. Conventional procedures may be employed to obtain the iso-hexanes and isoheptanes together or as separate fractions, usually with a maximum boiling point of about 210° F. When the iso-hexanes and isoheptanes are recovered as separate fractions, n-hexane is removed by an intermediate fractionation step. The isoparaffin stocks thus obtained will have a greatly reduced sulfur content compared to the total pentane-free gasoline or to

the residual fraction comprising n-heptane and heavier hydrocarbons since the major portion of the sulfur impurities is concentrated in the highest boiling hydrocarbon fraction. When the combined or separate overhead fractions have an end point below around 190-200° F., the sulfur compounds comprise mainly ethyl sulfide. Thus, a treatment with our reagent for the removal of alkyl sulfides will effect a significant further reduction in the sulfur content. Also, when the iso-paraffins are not segregated and the pentane-free gasoline is merely subjected to a de-oiling fractionation for the removal of high-boiling ends, the sulfur content of the de-oiled gasoline may be reduced to a satisfactory low figure by regulation of the end point of the overhead fraction.

The various operations of our process may be illustrated by reference to the drawing which shows one of the arrangements of equipment which are suitable for practicing our invention.

The sour substantially butane-free gasoline enters by line 1 to column 2 wherein the C₅ hydrocarbons are taken overhead through line 3 to sweetening unit 4 and thence by line 5 to column 6. In column 6 the isopentane is taken overhead through line 7, while the n-pentane is removed from the kettle through line 8 to storage 9. The isopentane passing through line 7 may pass directly to storage through by-pass line 7a, or it may pass through line 10 and dehydrator 11 to alkyl sulfide removal reagent (anhydrous cupric chloride) in vessel 12. From 12 the isopentane passes through line 13 to storage 14.

The pentane-free bottoms fraction from column 2 passes through line 15 to sweetening unit 16, thence by line 17 to column 18. Column 18 is operated to take the desired portion of the pentane-free gasoline overhead through line 19, while the heavy bottoms pass through line 20 to storage 21. The overhead fraction passes through lines 19 and 19a to storage 20. Alternately the stream may pass through lines 19 and 22 to dehydrator 23, alkyl sulfide removal unit 24 and then by line 25 to storage 26. In one adaptation of our process, column 18 becomes the so-called de-oiling column for the production of oil-free pentane-free gasoline by the removal of high-boiling fractions from the pentane-free material. In other adaptations, column 18 may be replaced by a series of columns in which isohexane and isoheptane fractions are segregated from the corresponding normal paraffins and higher-boiling constituents of the pentane-free gasoline. In such a sub-division of the fractionation operations necessary facilities are provided for the operation of the separate columns and the isoparaffin fractions may be combined or stored separately with intervening treatment for the removal of alkyl sulfides if desired.

The sour gasoline charge to our process should be substantially butane-free to avoid inclusion of butane in the isopentane stock. This condition is normally obtained since the butane fraction is ordinarily carefully segregated for other uses.

We have noted that the sequence of operations which is outlined above is necessary to obtain products of the lowest sulfur content and highest response to tetraethyl lead. Thus the separation of the C₅ hydrocarbons prior to sweetening results in a lower sulfur content for the pentane-free gasoline fraction than when the sweetening is performed on the total or butane-free gasoline stream. In effect our process results in the removal of sulfur from the C₅ and higher-boiling hydrocarbon fraction through inclusion of a

larger amount of sulfur in the C₆ fraction but without causing thereby any increase in the sulfur content of the isopentane which is one final product of our process. This feature of our process is apparently based on the distribution of mercaptans and disulfides throughout the entire gasoline boiling range in a manner not clearly discernible from the boiling points of the pure sulfur compounds. By our initial fractionation, a larger proportion of the mercaptan sulfur is included in the C₅ fraction than would be predicted from the mercaptan boiling points listed. Thus when the fractionation precedes sweetening, the mercaptans are partly removed in the overhead pentane fraction and are subsequently converted to disulfides and concentrated in the less valuable n-pentane fraction by the fractionation which segregates isopentane. When the sweetening precedes the depentanizing step, the disulfides formed are absent from the C₅ fraction but are distributed throughout the C₆ and heavier fraction in the subsequent fractionation of this material. This distribution results in a higher sulfur content for the intermediate boiling C₆ and C₇ isoparaffins and/or for the oil-free pentane-free gasoline.

It will also be noted from the above description that in the separation of isopentane from n-pentane, the methyl sulfide present is concentrated almost entirely in the isopentane fraction although the boiling point of methyl sulfide is slightly higher even than that of n-pentane.

By our initial fractionation, the methyl and ethyl mercaptans and a part of the isopropyl, t-butyl and n-propyl mercaptans present in the sour gasoline are taken overhead with the C₅ hydrocarbons. This distillation effect is beneficial since the sweetening step converts these mercaptans to disulfides and the boiling point difference is then so great that the disulfides are completely concentrated in the n-pentane fraction. The inclusion of methyl and ethyl mercaptans in the C₅ fraction is of additional benefit since the disulfides formed by sweetening have boiling points of 244° F. and 307° F., respectively, and thus are taken largely into a hydrocarbon fraction boiling as high as 300° F. When methyl and ethyl mercaptans are removed by our process from the C₅ and heavier fraction prior to sweetening there is a corresponding reduction in the sulfur content of the higher boiling stocks obtainable from the pentane-free gasoline.

The isopentane fraction produced by our process has a very low sulfur content which consists almost entirely of methyl sulfide. In some cases the sulfur content is low enough to make further desulfurization unnecessary. In other instances the methyl sulfide content may be large enough to justify further treatment. We prefer to pass the isopentane stream first through an efficient dehydrator to remove water and then through a bed of substantially anhydrous cupric halide reagent, usually the chloride, which effectively removes the methyl sulfide.

The C₆ and heavier fraction which has a reduced mercaptan content following the depentanizing operation is sweetened for conversion of the remaining mercaptans to disulfides. Since methyl mercaptan is absent, the disulfides formed boil above about 300° F. and are thus almost completely absent from intermediate fractions such as isohexanes and isoheptanes with end points below about 200° F., and are only partially included in fractions with end points up to about 300° F. The sulfur content of the lower-boiling

stocks obtained by fractionation of the sweetened pentane-free gasoline of our process is thus reduced by the distillation step. A treatment over the alkyl sulfide removal reagent as described for the isopentane effectively removes the ethyl sulfide also from the oil-free pentane-free gasoline or the lower-boiling isoparaffin fractions thereof.

The following example will further illustrate the improved results to be obtained by our process. However, since many modifications of the disclosed process are possible, no limitation is implied.

A sour butane-free natural gasoline had a total sulfur content of 0.045 per cent. This gasoline, which was to serve as a source of isopentane and of special high-octane blending stocks, was processed according to our invention, with the results recorded below. Other processing methods than those embodied in our invention were also evaluated, and the comparative results are included to show the superiority of the present invention.

A portion of the sour gasoline was fractionated to remove the C₅ hydrocarbons. The distribution of sulfur was as follows:

Sample:	Per cent sulfur
Butane-free sour gasoline	0.045
Sour C ₅ fraction	0.036
Sour C ₅ and heavier pentane-free fraction	0.055

Fractionation of the sour C₅ fraction without sweetening gave the following results:

Sample:	Per cent sulfur
Sour isopentane	0.037
Sour n-pentane	0.037

When the C₅ fraction was sweetened prior to isopentane production according to our invention, the resultant fractions had these sulfur contents:

Sample:	Per cent sulfur
Isopentane from sweetened C ₅ fraction	0.003
n-Pentane bottoms	0.061

Thus over 90 per cent of the sulfur occurring in the C₅ fraction is concentrated in the n-pentane bottoms by our process. This removal of sulfur from the isopentane is not possible when the sour C₅ mixture is fractionated into iso and normal pentane prior to sweetening.

When the isopentane was dried and passed over anhydrous cupric chloride reagent the sulfur content was reduced from 0.003 to 0.0008 per cent.

The sour pentane-free gasoline fraction (the bottom product) having a sulfur content of 0.055 per cent was sweetened and then fractionated, taking varying volume percentages overhead to correspond to various oil-free naphtha cuts. The 60 sulfur content of the fractions was as follows:

Sample:	Per cent sulfur
80 per cent overhead cut	.0130
90 per cent overhead cut	.0130
96.6 per cent overhead cut	.0170

The 80 per cent overhead cut was dehydrated and passed over anhydrous cupric chloride reagent. The treated material had a sulfur content of 0.010 per cent.

A portion of the sweetened pentane-free gasoline was also fractionated by a series of operations which produced isohexane and isoheptane stocks of high purity. The isohexane fraction had a total sulfur content of 0.007 per cent, while the 75

isoheptane contained 0.015 per cent sulfur. The isoparaffin fractions were combined and treated over anhydrous cupric chloride reagent to produce a high octane blending stock with a sulfur content of 0.006 per cent.

To compare the results listed above with the conventional process of treating natural gasolines, a sample of the same sour butane-free gasoline was sweetened prior to depentanization. The other segregating steps were carried out with the following results:

Sample:	Per cent sulfur
Sour butane free gasoline	.045
Sweet butane free gasoline	.045
C ₅ fraction from above	.002
C ₅ and heavier fraction from above	.092
Isopentane from C ₅ fraction	.003
n-Pentane from C ₅ fraction	.001

These results show that while the isopentane produced had a sulfur content comparable with that produced by our new process, the sulfur content of the pentane-free fraction increased from 0.055 to 0.092, an increase of almost 65 per cent. The principal sulfur reduction was in the n-pentane fraction which is the least valuable blending stock. Subsequent fractionation of the C₅ and heavier fraction gave isohexanes and isoheptanes with objectionably high sulfur contents removable only with difficulty and at great expense.

The improved response to tetraethyl lead resulting from our new process is illustrated by the following comparison of the above-described pentane-free gasoline:

Sample	Per cent sulfur	A. S. T. M. octane number			
		0 cc. TEL	1 cc.	2 cc.	3 cc.
C ₅ and heavier fraction (produced by new process)	0.055	59.0	71.0	76.1	79.0
C ₅ and heavier fraction (depentanized after sweetening)	.092	58.9	67.1	72.0	75.0

When the pentane-free fractions listed above were fractionated to remove absorption oil and heavy ends, about 4 per cent of the material was removed as bottoms. The pentane-free, oil-free gasoline produced by our new process had a sulfur content of 0.017 per cent, while that produced by the prior process had a sulfur content of 0.023 per cent. Thus, our process reduced the sulfur content of the oil-free gasoline more than 35% below that obtained in the conventional process.

The pentane-free gasoline produced by our new process was fractionated to produce an overhead fraction with an end point of 185° F., and this special naphtha after treatment to remove alkyl sulfides required only 55 per cent of iso-octane in preparing a 7 pound Reid vapor pressure 100 octane blend. The corresponding pentane-free stock containing 0.023 per cent sulfur as stated above required almost 59 volume per cent of iso-octane to prepare the same blend.

The terms "butane-free" and "pentane-free," as employed herein, denote hydrocarbon mixtures containing not more than five (5) volume per cent of butane or pentane which have been substantially removed by efficient fractionating columns.

The sweetening operations indicated in our process may be any conventional sweetening methods wherein the mercaptans are substantially completely converted to other forms, notably the disulfides, without any increase in the

total sulfur content of the stocks being treated. Also included are supplemental sweetening methods wherein mercaptans are partially removed as such, since such modifications do not alter the fundamental features of our process within the scope of the foregoing disclosure.

We claim:

1. The process of producing isopentane from a sour hydrocarbon oil in the gasoline range which is substantially butane and hydrogen sulfide free which comprises fractionating said oil to obtain as the overhead product a fraction comprising the pentanes containing mercaptans and methyl sulfide, sweetening said pentane fraction, fractionating the sweetened pentane fraction to recover as the overhead product a fraction comprising essentially isopentane and containing methyl sulfide but essentially free from other forms of sulfur, and treating said isopentane fraction to remove said methyl sulfide and recover isopentane essentially free from sulfur.

2. The process of producing an isopentane fraction which comprises fractionating sour gasoline which is substantially butane- and hydrogen sulfide-free, to recover a fraction comprising essentially pentanes and containing lower mercaptans and methyl sulfide, sweetening said fraction to convert said mercaptans to disulfides, fractionating said sweetened fraction and recovering a normal pentane fraction containing said disulfides and an isopentane fraction containing said methyl sulfide, and treating said isopentane fraction to remove said methyl sulfide therefrom and form substantially pure isopentane.

3. The process of preparing a fraction of hydrocarbons consisting essentially of isopentane which comprises fractionating a sour hydrocarbon oil in the gasoline range which is substantially butane and hydrogen sulfide free into a pentane fraction and a heavier fraction, separately sweetening said fractions in such manner as to convert mercaptans therein to disulfides, and separately fractionating the sweetened fractions to recover from said pentane fraction a light fraction of isopentane and a heavier n-pentane fraction in which the high boiling sulfur compounds are concentrated, and to recover from said first-named heavier fraction one or more light fractions comprising isohexane and isoheptane and a heavier fraction.

4. The process of preparing a fraction of hydrocarbons consisting essentially of isopentane which comprises fractionating a sour hydrocarbon oil in the gasoline range which is substantially butane and hydrogen sulfide free into a pentane fraction and a heavier fraction, separately sweetening said fractions in such manner as to convert mercaptans therein to disulfides, separately fractionating the sweetened fractions to recover from said pentane fraction a light fraction of isopentane and a heavier n-pentane fraction in which the high boiling sulfur compounds are concentrated, and to recover from said first-named heavier fraction one or more light fractions comprising isohexane and isoheptane and a heavier fraction, and separately treating the light fractions so produced to remove alkyl sulfides therefrom.

5. The process of recovering high octane number gasoline blending stock of low sulfur content from sour hydrocarbon oil in the gasoline range which is substantially butane and hydrogen sulfide free which comprises fractionating said oil to remove overhead pentanes and a large proportion of the sulfur compounds and form a bottom

product, sweetening the bottom product from said fractionation to convert remaining mercaptans therein to disulfides, and fractionating the sweetened bottom product to recover at least one fraction of substantially pentane-free and mercaptan-free material in the gasoline range.

6. The process of recovering high octane number gasoline blending stock of low sulfur content from sour hydrocarbon oil in the gasoline range which is substantially butane and hydrogen sulfide free which comprises fractionating said oil to remove overhead pentanes and a large proportion of the sulfur compounds and form a bottom product, sweetening the bottom product from said fractionation to convert remaining mercaptans therein to disulfides, fractionating the sweetened bottom product to recover at least one fraction of substantially pentane-free and mercaptan-free material in the gasoline range, and subjecting said pentane-free material to treatment to remove alkyl sulfides therefrom and form essentially sulfur-free material.

7. A process for the production of isopentane and pentane-free light gasoline of lowered sulfur content from a sour butane and hydrogen sulfide free hydrocarbon mixture containing same which comprises fractionating said mixture to produce an overhead fraction consisting of C₅ hydrocarbons and a bottoms fraction consisting of substantially pentane-free gasoline, treating said fractions in separate units to convert the mercaptans contained therein to disulfide form, fractionating said C₅ hydrocarbon fraction to produce an overhead fraction comprising isopentane and a bottoms fraction comprising n-pentane, fractionating said substantially pentane-free gasoline to remove components boiling substantially above the gasoline range therefrom, and thereby obtaining an isopentane stock and a substantially pentane-free gasoline stock of lowered sulfur content and improved response to tetraethyl lead.

8. The process of claim 7 wherein the isopentane stock and the pentane-free gasoline stock are treated in substantially anhydrous condition with a reagent comprising substantially anhydrous cupric chloride whereby alkyl sulfides are removed and said stocks of lowered sulfur content and improved response to tetraethyl lead are obtained.

9. The process of claim 7 wherein the said pentane-free gasoline stock subsequent to sweetening is fractionated to produce an overhead fraction substantially lower boiling than n-heptane and a bottoms fraction comprising n-heptane and higher-boiling hydrocarbons, and wherein said overhead fraction and the isopentane stock are treated in substantially anhydrous condition with a reagent comprising substantially anhydrous cupric chloride whereby alkyl sulfides are removed and said isopentane stock and said substantially pentane-free n-heptane-free gasoline are obtained with lowered sulfur content and improved response to tetraethyl lead.

10. A process for the production of isopentane and pentane-free light gasoline of lowered sulfur content from a mixture comprising principally hydrocarbons of 5 to 8 carbon atoms inclusive together with sulfur impurities including mercaptans and alkyl sulfides which comprises fractionating said mixture to produce an overhead fraction consisting of C₅ hydrocarbons and a bottoms fraction consisting of substantially pentane-free gasoline, treating said fractions in separate units to convert the mercaptans contained there-

in to disulfide form, fractionating said C₅ hydrocarbon fraction to produce an overhead fraction comprising isopentane and a bottoms fraction comprising n-pentane, fractionating said substantially pentane-free gasoline to remove components boiling substantially above the gasoline range therefrom and thereby obtaining an isopentane stock and a substantially pentane-free gasoline stock of lowered sulfur content and improved response to tetraethyl lead.

11. A process for the production of high octane isoparaffinic gasoline of lowered sulfur content from a mixture comprising principally hydrocarbons of 5 to 8 carbon atoms inclusive, together with sulfur impurities including mercaptans and alkyl sulfides which comprises fractionating said mixture to produce an overhead fraction consisting of C₅ hydrocarbons and a bottoms fraction consisting of substantially pentane-free gasoline, treating said fractions in separate units to convert the mercaptans contained therein to disulfide form, fractionating said C₅ hydrocarbon fraction to produce an overhead fraction comprising isopentane and a bottoms fraction comprising normal pentane, fractionating said substantially pentane-free gasoline to produce an isohexanes fraction and an isoheptanes fraction and combining said isohexanes and isoheptanes fractions to produce a high octane isoparaffinic gasoline of lowered sulfur content and improved response to tetraethyl lead.

12. The process of claim 11 in which the high octane isoparaffinic gasoline is treated in substantially anhydrous condition with substantially anhydrous cupric chloride for the removal of alkyl sulfides.

13. A process which comprises fractionating a sour hydrocarbon oil in the gasoline range which is substantially butane and hydrogen sulfide free to obtain as an overhead product a fraction comprising the pentanes and as the bottom product a heavier substantially pentane-free fraction, sweetening said bottom product to convert mercaptans therein to disulfides, and fractionating said sweetened bottom product to separately recover isoheptane and isoheptane fractions of greatly reduced sulfur content and increased tetraethyl lead response.

14. A process for the production of high octane isoparaffinic gasoline fractions of lowered sulfur content from a butane-free predominantly saturated gasoline having a boiling range of from about 70° F. to about 300° F. and containing sulfur impurities including mercaptans and alkyl sulfides which comprises fractionating said gasoline to produce fractions consisting essentially of hydrocarbons of the same number of carbon atoms, separately sweetening said fractions to convert the mercaptans to disulfides, further fractionating the sweetened fractions to separate a lower boiling isoparaffinic fraction from higher

boiling normal paraffin fraction containing the disulfides, and recovering thereby isoparaffinic gasoline fractions of lowered sulfur content.

15. The process of claim 1 in which the isoparaffinic fractions are treated in substantially anhydrous condition over a reagent comprising anhydrous cupric chloride for the removal of alkyl sulfides.

16. A process for the production of high octane isoparaffinic gasoline fractions of lowered sulfur content from a butane-free predominantly saturated gasoline having a boiling range of from about 70° F. to about 300° F. and containing sulfur impurities including mercaptans and alkyl sulfides which comprises fractionating said gasoline to produce an overhead fraction consisting of C₅ hydrocarbons and a bottoms fraction consisting of substantially pentane-free gasoline, treating said fractions in separate units to convert the mercaptans contained therein to disulfide form, fractionating said C₅ fraction to produce an overhead fraction comprising isopentane and a bottoms fraction comprising normal pentane, fractionating said substantially pentane-free gasoline to produce successively higher boiling fractions comprising respectively isohexanes, normal hexanes, isoheptanes, normal heptanes, isoctanes, normal octanes and isononanes with the highest boiling of said successive fractions having an end-point below about 300° F. and the total volume of said fractions not exceeding about 96 per cent of the total volume of pentane-free gasoline, and thereby separating and recovering by means of said fractionations high octane isoparaffinic gasoline fractions from low octane normal paraffin gasoline fractions.

17. A process as in claim 2 wherein the isoparaffinic gasoline fractions are treated for removal of alkyl sulfides.

18. A process for the production of high octane number isoparaffinic gasoline blending stocks of low sulfur content from sour hydrocarbon oil in the gasoline range which comprises fractionating said oil to remove overhead pentanes and a large proportion of the sulfur compounds, sweetening the bottom product from said fractionation consisting of hexanes and heavier hydrocarbons to convert remaining mercaptans therein to disulfides, and fractionating the sweetened bottom product in a series of distillation steps to recover fractions comprising isoparaffins of the same number of carbon atoms separate from the corresponding low octane number normal paraffin fractions.

19. A process as in claim 7 in which the substantially pentane-free sweetened gasoline is fractionated to remove components boiling above about 300° F.
